UNITED STATES PATENT OFFICE.

GEORGE C. WEIDEMAN, OF CLEVELAND, OHIO, ASSIGNOR OF ONE-HALF TO THOMAS J. SMITH, OF CLEVELAND, OHIO.

FURNACE.

Application filed June 18, 1924. Serial No. 720,717.

This invention relates to furnaces and has particular reference to a furnace for heating dwelling houses.

The primary object of the present invention is to provide a particularly efficient furnace which shall utilize a relatively high percentage of the heat units developed in the combustion chamber.

Another object is to provide a furnace which shall be simple in construction, inexpensive to manufacture and which may be easily and quickly cleaned.

A still further object is to provide a furnace of the aforesaid character which shall present a particularly neat appearance and which shall occupy a relatively small floor space.

With these and other objects in view, the invention consists in the various novel features of construction and arrangement or combination, all of which will be fully described hereinafter and pointed out in the appended claims.

In the drawing accompanying and forming part of this application, Fig. 1 is a vertical sectional view through a furnace constructed in accordance with my invention; Fig. 2 is a transverse sectional view taken on the line 2—2 of Fig. 1; and Fig. 3 is a detail sectional view corresponding to the line 3—3 of Fig. 2.

Describing the various parts by reference characters 1 and 2 denote upper and lower base rings which may be in the form of castings. Each ring is provided with vertically extending circumferential flanges 3 and 4 which are arranged in spaced relation. Flanges 3 are adapted to receive a sheet metal cylinder 5 which encloses a space that serves as the fresh air distributing chamber 6, and flanges 4 are also adapted to receive a sheet metal cylinder 7 which together with cylinder 5 defines a circular ring shaped chamber 8 which I shall term the smoke ring chamber. The upper base ring 1 is also provided with an upwardly extending circumferential flange 9 and an inwardly directed circumferential shelf 10. The shelf 10 is adapted to receive and support a circular sheet metal plate 11 which closes the top of the fresh air distributing chamber 6. This plate is provided with a plurality of apertures arranged in circular form and each aperture receives a fresh air pipe 13 which extends upwardly through a suitable

aperture formed in an upper plate 14. A wall of heavy asbestos 16 is disposed about the pipes 13 so as to form an enlarged cylinder as clearly shown in Figs. 1 and 2 and in fact this cylinder defines the combustion chamber 17 of the furnace. A sheet metal cylinder 18 is engaged over flange 9 in the upper base ring and this cylinder merely serves as a protective housing for the furnace and as an enclosure therefor. An opening 19 is formed in this outer cylinder, about which is fastened a fire door 20 in the usual manner.

The fresh air pipe designated 13^a immediately in front of the fire door opening 19 extends downwardly only as far as the top of door opening as shown in Figs. 1 and 3 so as to provide ready access to the interior of the combustion chamber. The bottom of pipe 13^a is closed by a cap 21 and this pipe is tapped into the adjacent fresh air pipes 3 by suitable horizontally disposed pipes 22.

A top ring 23 which may be a casting is provided with a horizontal and outwardly projecting circumferential shelf 24 and a similar but inwardly projecting shelf 25. The ring is supported by the shelf 24 resting on the top edge of the enclosing cylinder 18 and projecting downwardly inside of the cylinder where it may be fastened by bolts (not shown) or in any other suitable manner. The inner shelf 25 engages the upper plate 14 and may also be fastened thereto if desired. The plate 14 is formed with an upwardly extending cylinder 26 which lies within the circle defined by the fresh air pipes 13, and the top of this cylinder is closed by a sheet metal cap 27. A hood 28 is applied to the top of the ring 23 and forms an enclosure 29 which serves as the hot air distributing chamber and from which suitable distributing pipes 30 lead.

Cylinder 26 is provided with a circumferential series of apertures, into each of which projects one end of an elbow 32. The opposite end of each of these elbows is connected to a pipe 33 which is arranged centrally within a fresh air pipe 13, and the lower ends of pipes 33 are each connected to an elbow 34 which extends through cylinder 5 and into the smoke ring chamber 8. The smoke ring chamber is provided with a suitable outlet pipe 35 which is adapted to connect with a chimney 36. A second con-

nection with the chimney is also provided by means of a pipe 37 which connects with the top of cylinder 26 and this pipe is preferably provided with a damper 38 so that it may be closed under normal operating conditions of the furnace as will be explained hereinafter.

In the present instance I have indicated an oil burner as the source of heat, this 10 burner consisting essentially of a motor driven fan 40 which delivers oil and air in an atomized condition to the burner bowl 41. This feature of my furnace forms no 15 part of the present invention and a detailed description thereof is deemed unnecessary. It will of course be understood that any 20 suitable burner, for oil or gas could be used or even a grate substituted therefor so as to enable the use of coal or other solid fuel.

20 In operation, the burner is lighted which heats the combustion chamber 17 and the exterior surfaces of pipes 13 and 13^a. If the chimney has a poor draft, damper 38 may be opened to start the draft up the chimney, 25 after which this damper is closed. The heat and products of combustion pass upwardly into chamber 26, then through elbows 32 and downwardly through pipes 33 and elbows 34 into the smoke ring 8, from whence they 30 pass through discharge pipe 35 to the chimney 36. This passage of the products of combustion heats the sheet metal cylinder 26 and elbows 32 which in turn impart their heat to the distributing chamber 29. Also 35 pipes 33 become heated and impart their heat to the interior of fresh air pipes 13. The elbows 34 being disposed within the 40 fresh air chamber, and the smoke ring 8 encircling this chamber, impart their heat thereto before the products of combustion escape up the chimney 36. Meanwhile the 45 heating of these various parts has caused a draft of fresh air to be drawn through inlet opening 45 into the fresh air chamber 6. The fresh air is warmed in this chamber 50 by contact with elbows 34 and sheet metal cylinder 5. This warm air then flows upwardly through pipes 13 and also through horizontal pipes 21 and thence upwardly 55 through pipe 13^a. During this upward flow, the previously warmed fresh air is now heated to a high degree due to its contact with the hot surfaces of pipes 13 and 13^a and also with the hot surfaces of the 60 combustion pipes 33 arranged within pipes 13. It is thus evident that the fresh air is heated by two different sources of heat. The heated 65 fresh air rises to the distributing chamber 29, where it also receives heat from the cylinder 26, cover plate 27 and elbows 32. From the distributing chamber the heated air is led to the rooms to be heated by pipes 30.

If desired, the furnace may be spaced a 65 suitable distance from the chimney 36 so

that the horizontal pipe which connects outlet 35 with the chimney might be enclosed by a suitable housing which would serve as a clothes drier, the heat for this drier being supplied by the aforementioned horizontal 70 section of the flue pipe.

With a furnace constructed in accordance with my invention, a huge percentage of the heat which ordinarily escapes unused to the chimney, is utilized by conducting it 75 through the pipes 33 and into the smoke ring chamber 8. In actual operation, the discharge pipe 35 remains sufficiently cool to place the hand thereon. If, however, the damper 38 is opened so that the furnace 80 functions as the usual type, the pipe 37 becomes so hot that it cannot be touched. This clearly demonstrates that the ordinary furnace wastes a high percentage of the heat 85 while this heat which is ordinarily lost is utilized by my improved form of construction.

The furnace is easily dismantled for 90 cleaning by removing the hood 28 and cover plate 27. A brush may then be inserted through the combustion pipes 33 to clean the soot therefrom.

While I have shown and described a furnace of the warm air type, it is obvious 95 that the same principle could be used equally well for steam, hot water or other fluid types of furnaces.

Having thus described my invention, what I claim is:

1. A furnace of the character set forth 100 comprising a combustion chamber including a plurality of conduits each adapted to conduct a fluid to be heated, the upper ends of said conduits being connected with a distributing chamber and the lower ends thereof being connected with a fluid supply chamber, a discharge chamber adjacent said fluid supply chamber and having an outlet, a plurality of pipes communicating with the upper portion of said combustion chamber 105 and disposed within said conduits and connected to said discharge chamber, said pipes being adapted to conduct the heat and products of combustion from the upper portion of said combustion chamber downwardly 110 through said conduits and into said discharge chamber whereby to supply heat to the interior of said conduits and means for heating the exterior of said conduits.

2. A furnace of the character set forth 115 comprising a combustion chamber including a plurality of conduits each adapted to conduct a fluid to be heated, a wall of heat insulating material surrounding said conduits, a distributing chamber arranged within the upper portion of said combustion chamber, the upper ends of said conduits being connected with said distributing chamber and the lower ends thereof being connected with a fluid supply chamber, a dis- 125

charge chamber adjacent said supply chamber and having an outlet therein, means for heating said combustion chamber and the exterior of said conduits, means communicating with said distributing chamber at one end and with said discharge chamber at the other end for conveying the products of combustion from said distributing chamber downwardly through said conduits and into said discharge chamber whereby to provide additional heat for the fluid to be heated.

3. A furnace of the character set forth comprising a pair of substantially annular concentric sheet metal cylinders arranged in spaced relation, the smaller of said cylinders defining a fluid supply chamber and the larger of said cylinders defining a discharge chamber, a plurality of conduits connected with said supply chamber and extending upwardly, said conduits being arranged in an annular formation to enclose an area of 360° and having a heat insulating wall surrounding the same, the upper end of said combustion chamber being closed and a plurality of pipes extending from the upper portion of said combustion chamber downwardly through said conduits and into said dis-

charge chamber, means for supplying heat to said combustion chamber and a hood fitted over the upper end of said conduits 30 and defining a distributing chamber.

4. A furnace of the character described comprising a hollow base divided into a fluid supply chamber and a discharge chamber, a combustion chamber carried by said base and having a distributing chamber arranged within the upper portion thereof, a series of conduits arranged within said combustion chamber and communicating at their lower ends with said fluid supply chamber 35 and at their upper ends with said distributing chamber, said distributing chamber being in open communication with the upper ends of said conduits and a series of pipes communicating with said distributing chamber at their upper ends and extending downwardly through said conduits respectively and connected at their lower ends with said discharge chamber whereby to heat the interior of said conduits and means for heating the exterior of said conduits. 50

In testimony whereof, I hereunto affix my signature.

GEORGE C. WEIDEMAN.
